Inventor

Ralph A. Long,

By Samuel Henick

Attorney

UNITED STATES PATENT OFFICE.

RALPH AUSTIN LONG, OF TAMAQUA, PENNSYLVANIA, ASSIGNOR TO ATLAS POWDER COMPANY, OF WILMINGTON, DELAWARE, A CORPORATION OF DELAWARE.

ELECTRODE.

Application filed March 1, 1922. Serial No. 540,107.

To all whom it may concern:

Be it known that I, RALPH AUSTIN LONG, a citizen of the United States, residing at Tamaqua, in the county of Schuylkill and 5 State of Pennsylvania, have invented certain new and useful Improvements in Electrodes, of which the following is a specification.

My invention relates to electrodes in which the anode member consists of thin 10 platinum sheeting or the like. Where it is necessary to employ platinum as the anode material in electrodes, such metal is always used in the form of very thin sheets. This practice is due entirely to the high cost of 15 the metal. The anode members of electrodes as now used, are of two general types; one where a single sheet of platinum is used and is reinforced on one side by some base metal such as lead or copper; the other, in 20 which one or more smaller sheets are attached to the lower portion of a common pole or rod and hang downwardly from it or extend away from it on either side.

One form of the first type consists of a 25 lead slab covered on one face with a thin sheet of platinum. With the platinum facing the inside of the tank the slab is pressed against the open end of the cell, or electrolyzing tank, and is bolted to the sides and 30 bottom of the tank but is insulated from the same. Thus the anode of such an electrode serves as one end of the electrolytic cell. The cathode member consists simply of an 35 iron or copper grid placed directly in front of the platinum face. The source of electricity is attached to the back or exposed portion of the lead slab.

In one form of the second type a thin 40 platinum sheet is attached to the lower portion of a pole, rod or a piece of base metal of any desired shape, which is protected from chemical and electro-chemical action by any of the well known methods. This sheet may be attached at one of its edges 45 and hang downwardly from the protected base metal. If the base metal is a rod, the rod may be attached to the middle of the platinum sheet, and the sheet extend away on either side. Or, a number of sheets of 50 platinum may be attached to a portion of some protected base metal and hang downwardly from it, or extend out on either side of it or both. The protected base metal extends above the surface of the solution where 55 it is connected to the current supply. The

cathode member of such an electrode consists of two or more sheets of iron or some similar metal, electrically connected to each other and so arranged that a sheet of iron, or the like, is found opposite each face of 60 the platinum sheets.

Electrodes of the first class are very rugged, and require little attention after 65 they are once assembled. Nevertheless, they are difficult to assemble; the slabs of lead faced with platinum are cumbersome to handle in commercial sizes and but one side of the platinum sheet is of use. The side of the platinum sheet next to the lead slab is, of course, of no service because it is not exposed to the action of the electrolyte. 70

Electrodes of the second type are easily made, are not so difficult to assemble as the first type and use both sides of the platinum sheets. But since they are made of thin 75 sheets of platinum they are inherently flimsy and must be handled with great care to prevent tearing or distorting of the sheets. Special precautions must be taken to prevent them from falling against the iron 80 cathode sheets and short circuiting the electrode. Due to this same lack of rigidness, such electrodes are limited as to their size and capacity.

The object of my invention is to provide 85 an electrode, the anode of which is platinum or some similar metal, that can be easily constructed and assembled; one that will require little attention; one that will retain its ruggedness, irrespective of its size; and 90 one in which both sides of the platinum are available for use. Briefly my invention includes a hollow platinum cylinder as the anode, resting between two hollow concentric iron cylinders as cathodes. The current 95 may be led into the platinum cylinder by means of one or more rods or columns of some base metal which are protected from chemical and electrochemical action by any of the ordinary methods. For instance, one 100 or more pieces of heavy glass tubing can be welded to the cylinder in such a manner, that when mercury is poured into the glass tube and the column of mercury connected with the source of current supply, electrical 105 contact is made between the mercury and the platinum cylinder. The platinum cylinder may also be supplied with current by welding to it one or more rods of some base metal which have previously been covered 110.

with a sleeve of some resistant metal such as platinum.

My invention can be more fully understood by reference to the accompanying drawings in which—

5 Fig. 1 is a perspective view;

Fig. 2 is a plan view; and

Fig. 3 is a fragmentary vertical section.

5 5 is the hollow platinum cylinder which rests between the two hollow concentric iron cylinders 6—6. 7—7 designate two positive poles of the electrode. These electrodes may consist of glass tubes 8 welded to the cylinder and filled with mercury 9, or two metal rods such as copper covered with a sleeve of thin platinum and welded to the cylinder. The two iron cylinders are held in place and connected electrically by the two stirrups 10—10 of angle iron. These stirrups 10 are bolted or screwed to the outside of the outer cylinder and the inside of the inner cylinder, as indicated at 11. 12—12 are pieces of insulating material, such as bakelite or hard rubber, that fit into vertical slots 13 cut opposite each other in the two iron cylinders 6—6. The insulating pieces fit tightly against opposite sides of the platinum cylinder and hold it firmly in place equidistant between the two iron cylinders. A 20 copper bar 14 is bolted to the outer iron cylinder, which conducts the current away from the electrode.

From the above description the novel and advantageous features of my invention will 35 be quite apparent. The thin platinum in the form of a cylinder is self-supporting and rigid. It requires no reinforcing, and may be made of any desirable size without detracting from its rigidness. Its construction is of the simplest, and its fabrication cost is therefore almost negligible. The assembling of this electrode involves merely placing the platinum cylinder between the two concentric iron cylinders and sliding 40 the insulating strips in place. The support of these insulating strips combined with the inherent rigidness of the cylindrical form, eliminates all danger of the platinum touching the iron cylinders and short circuiting 45 the electrode, although the platinum and iron cylinders are not more than one quarter of an inch apart. After being assembled the platinum anode is completely protected on all sides by the heavy iron cylindrical 50 cathodes. As both sides of the platinum are available for use, the capacity of the electrode is large in comparison with its size. The space between the two iron cylindrical 55 cathodes, and the cylindrical platinum anode 60 is free of all protrusions and the electrode rests upon iron legs constituted by the stirrups 10—10, about three or four inches above the bottom of the cell. The gases evolved upon the surface of the two iron 65 cathodes facing the platinum result in a

sucking action that draws the solution from the bottom of the tank up through the space between the two iron cylinders and out of the top of said space which causes a constant circulation of the cell liquor or electrolyte. This constant self mixing action of the electrode prevents the collection of slime or sludge at any point between the anode and cathode, and thus eliminates the danger of short circuits from this cause. 75 This danger is further prevented by the position of the electrode above the bottom of the tank, and by the absence of protrusions in the space between the anode and cathode.

Thus, in capitulation, it may be pointed out that the electrode of my invention, is rugged, compact, small in comparison to its capacity, free from all danger of short circuits, self mixing, of simple construction, and easily handled.

Having described my invention, what I claim is:

1. In combination a hollow cylinder of platinum or the like as an anode, placed between two hollow concentric metal cylinders, 90 which are electrically connected to each other and act as cathodes and spacing means for holding the said platinum cylinder concentrically within the last named cylinders.

2. In combination an anode consisting of a hollow platinum cylinder, held firmly in place between two hollow concentric iron cylinders by two or more pairs of insulating strips, which strips rest in vertical slots cut opposite each other in the iron cylinders 100 and press firmly against opposite sides of the platinum cylinder.

3. In combination an anode consisting of a hollow platinum cylinder, and a cathode, consisting of two hollow concentric iron cylinders, constituting a separate, distinct, and self-sustaining part, mechanically complete in itself.

4. In combination an anode consisting of a hollow platinum cylinder and a cathode consisting of a pair of iron cylinders between which the platinum cylinder is concentrically disposed.

5. In combination an anode which consists of a hollow platinum cylinder and a cathode which consists of a pair of iron cylinders between which the platinum cylinder is concentrically disposed and vertically disposed strips of insulating material between the anode and the cylinders of the cathode, 120 said cylinders of the cathode being vertically slotted for the reception of said insulating strips.

6. In combination an anode consisting of a hollow platinum cylinder having conducting elements projecting vertically therefrom, a cathode consisting of a pair of hollow iron cylinders between which the cylinder of the anode is concentrically disposed, said hollow iron cylinders being electrically 125 130

connected to constitute a cathode, an insulating strip between a cylinder of the cathode and a cylinder of the anode said cylinder of the cathode being vertically slotted for the reception of said strip and said strip being vertically channeled for the reception of said conducting element of the anode.

In testimony whereof I affix my signature in the presence of two witnesses.

RALPH AUSTIN LONG.
